[57] CLAIM

The ornamental design for a grass extracting device, as shown and described.

DESCRIPTION

FIG. 1 is a front elevational view of my new design of a grass extracting device;

FIG. 2 is a left-side elevational view thereof, the right-side elevational view being a mirror image of this view;

FIG. 3 is a back elevational view thereof;

FIG. 4 is an enlarged view of a portion shown in FIG. 2 taken in the direction of arrows 4—4;

FIG. 5 is a left-side elevational view of another embodiment of the invention, the right-side elevational view being the mirror image of this view;

FIG. 6 is a back elevational view of the embodiment shown in FIG. 5; and

FIG. 7 is an enlarged view of a portion shown in FIG. 5 taken in the direction of arrows 7—7.
